UNITED STATES PATENT OFFICE.

JOSEPH H. LALIBERTE, OF NASHUA, NEW HAMPSHIRE, ASSIGNOR TO NASHUA MANUFACTURING COMPANY, OF BOSTON, MASSACHUSETTS, A CORPORATION OF NEW HAMPSHIRE.

SPINNING FRAME.

Application filed November 24, 1924. Serial No. 751,798.

This invention relates to spinning frames and like machines used in the building of bobbins or other thread packages, herein-after for convenience referred to as "bobbins." It is the usual practice to wind or fill bobbins in a ring spinning frame, this machine being equipped with a builder motion which determines the manner in which successive layers of thread shall be wound on the bobbin. The present invention is especially concerned with machines of this type equipped with mechanism for building filling wound thread packages.

In winding thread on a bobbin to make a package of this type, the builder motion gives the ring rail a slow reciprocating motion, gradually increasing its elevation between successive reciprocations until the bobbin has been filled to the desired height. Usually these machines are equipped with a full bobbin stop motion which operates automatically to stop the machine when the filling of the bobbins has been completed. According to the common practice, the machine tender at this point starts up the machine again and immediately begins to wind down the ring rail, stopping the machine when the rail has been completely lowered. This results in winding the yarn or thread in a spiral around the bobbin and then winding a few turns of thread or yarn on the base of the bobbin. When the bobbins are subsequently loaded into the magazine of a loom, these turns must be unwound, and for this reason it is objectionable to wind an excessive quantity of yarn on the base of the bobbin. Where the winding down operation is performed by hand, however, it is inevitable that there will be a wide variation in results since the spindles rotate very rapidly, and a very small variation in the time taken by an operator to shut down the machine will, therefore, make a very substantial difference in the quantity of yarn that will be wound on the bases of the bobbins.

It is the chief object of the present invention, therefore, to improve the construction of spinning machines with a view to producing greater uniformity in that portion of the thread package which is formed by the winding down operation, and reducing the care and attention required by the operator in performing this operation. To this end the

invention provides a mechanism for automatically winding down the ring rail and so controlling the successive steps in this operation that the desired accuracy in the winding of the thread packages will be obtained.

It has been proposed heretofore to wind down the ring rail automatically at the conclusion of the bobbin building operation, but these mechanisms have not, so far as I am aware, been satisfactory due to the fact that the point at which the machine finally stops cannot be accurately controlled, with the result that an excessive variation is produced in the amount of thread wound on the bases of the bobbins. The present invention provides a mechanism that overcomes this objection.

The nature of the invention will be readily understood from the following description when read in connection with the accompanying drawings, and the novel features will be particularly pointed out in the appended claims.

In the accompanying drawings,

Figure 1 is a side elevation of a portion of a spinning frame showing only those parts of the machine with which the invention is more particularly concerned;

Figs. 2 and 3 are side elevations showing successive steps in the operation of winding down the ring rail and stopping the machine;

Fig. 4 is a side view, partly in cross-section, of the belt shifter and adjacent parts;

Fig. 5 is a transverse, cross-sectional view through the machine showing a portion of the mechanism which winds down the ring rail, certain of the parts being shown in elevation;

Fig. 6 is a side view of the more important parts of the builder mechanism;

Fig. 7 is a plan view of the clutch and adjacent parts;

Fig. 8 is an end view of one of the clutch parts; and

Fig. 9 is a side elevation of the clutch shifting lever.

In the machine shown the ring rail is indicated at 2, this rail being supported by a series of vertical rods, one of which is shown in Fig. 1 at 3. The lower end of this rod carries a foot which rests on a roll 4 supported at the outer end of an arm 5 which is

secured rigidly to a cross shaft 6. A weight 7, also fastened to the cross shaft, tends to operate through the connections just described to lift the ring rail 2. The movement of the ring rail, however, is controlled by a builder motion indicated in general at 8, Fig. 1, and shown more completely in Fig. 6. The lever 9 of the builder motion is connected by a chain 10 to a sector secured fast 10 on the rock shaft 6, a portion of this chain being wound on a drum 12, Fig. 6, so that as the lever 9 is reciprocated by the cam 13 during the operation of the machine, the ring rail 2 will be raised and lowered, but the 15 winding of the chain 10 from the drum 12 will allow the rail to rise, a step at a time, between successive reciprocations. This results in building up the bobbin by the usual filling wind process. All of the mechanism 20 so far described is constructed, arranged and operated in the usual manner.

The machine is equipped with mechanism for automatically stopping it, which comprises a belt shifter 15, Fig. 4, secured on the 25 end of a rod 16 and operative to shift the driving belt 17 from the fast pulley 18 on to the idle or loose pulley 19, or vice versa. The rod 16 is mounted in the frame to slide longitudinally. Adjustably secured to the end of this rod remote from the shifter 15 is a small bracket or arm 20 which is in line with another rod 21, also mounted to slide longitudinally in the machine. A strong spring 22 connected with this rod tends to move it toward the right, Figs. 1 to 3, and thus to act through the arm 20, rod 16 and shifter 15 to move the belt 17 from the fast pulley 18 on to the idle pulley 19 and thus stop the machine. Normally, however, the movement of the rod 21 under the influence of the spring 22 is 30 prevented by a pivoted latch 24 which engages a stop 25 adjustably secured to the rod 21.

This mechanism is under the control of a 45 part movable in conjunction with the ring rail. That is, a rod 27 is supported at its lower end by an arm 28, secured to the cross shaft 6, so that as this shaft is rocked by the builder motion during the progress of the 50 bobbin winding operation, the rod 27 will gradually be raised until, when the building of the bobbins has been completed, its upper end will strike the latch 24 and lift it. This releases the stop 25 and allows the spring 22 to 55 operate through the connections with the belt shifter to shut down the machine. The rod 27 is adjustably secured in the arm 28 so that it may be made to trip the latch 24 at any desired point in the rise of the ring rail 2.

The machine also includes a mechanism 60 which is brought into operation automatically upon the tripping of the latch 24 to wind down the ring rail. This mechanism comprises a clutch including a driving member 30

and a driven member 31, both mounted loosely on the shaft 32 of the builder motion. Preferably the part 30 is integral with a sprocket wheel 33 which is driven from the shaft 34, Fig. 5, through a sprocket chain 35. The other clutch member 31 is slideable on the shaft 32 into and out of clutching engagement with the member 30, and its position is controlled by a clutch lever 36 pivoted at 37, the lower end of this lever being forked to straddle the part 31 and having pins or rolls 38-38 which run in a groove 39 formed in the part 31. A spring 40, Fig. 1, tends to throw the sliding clutch member 31 into engagement with its cooperating member 30. Normally, however, the clutch is held out or disengaged by means of a collar 41 adjustably secured to the sliding rod 21, this collar bearing against the upper end of the clutch shifting rod 36. When the clutch part 31 engages the driving clutch member 30, rotation is thereby imparted to a cam 42, Figs. 1, 5 and 7, and this cam operates through a roll 43 to depress a lever 44 which is connected by means of a chain 45 to an arm 46 secured to the cross shaft 6, and thus lowers or winds down the ring rail 2.

When the machine is in operation the bobbin building process proceeds in the usual manner until the bobbins have been filled to the desired height. At this time the upper end of the rod 27 trips the latch 24, as above described, and as shown in Fig. 3. The spring 22 immediately acts to move the rod 21 to the right, but this movement is interrupted almost immediately by the engagement of the stop 25 with an arm 47 pivoted at 48, Fig. 1, on the machine frame, and adjustably secured by a bolt 49 to the upper portion of the rod 27 so that this arm 100 moves in conjunction with the ring rail. Upon the releasing of the stop 25 by the latch 24 the rod 21 is allowed to move just far enough to permit the spring 40 to throw in the clutch 30-31 before the arm 47 catches the stop 25 and interrupts the movement of the rod 21. This movement is not sufficient to shift the belt 17, but it does serve to initiate the operation of the mechanism that winds down the ring rail, this function being 110 performed by the cam 42, lever 44, and the connections between this lever and the cross shaft or rock shaft 6. As the ring rail moves downwardly the arm 47 and rod 27 of course move in conjunction with it, and as soon as the free end of the arm 47 slides down past the stop 25, the spring 22 then operates through the rod 21 and the connections with the shifter 15 to move the belt on to the loose pulley 19, thus stopping the machine. 120 It will thus be observed that while the action of the stopping mechanism is initiated by the rise of the ring rail, the completion of this operation is under the control of the arm 47 which also moves with, or in conjunction 130

with, the ring rail 2. The point at which the arm 47 permits the belt shifting mechanism to function can be adjusted with reference to the travel of the ring rail by loosening the 5 bolt 49 and moving the arm 47 up or down on the rod 27.

When the cam 42 has moved the lever 44 into its lowermost position, as shown in Fig. 5, and thus has completed the depression of 10 the ring rail, the upper end of a latch 50, Fig. 5, slips under the frame part 51 and locks the ring rail in its lowermost position. The latch 50 is pivoted to the outer end of 15 the lever 44, and a spring 52 is interposed between the latch and the lever in such a way as to hold the latch forward in its operative position. In order to release this latch it is simply necessary to push it backwardly 20 far enough to disengage its notch from the part 51.

As the clutch parts 30 and 31 continue to rotate after completing the winding down operation, a cam lug 53, Fig. 7, integral with the part 30, engages the inclined face of another cam lug 54 formed on the relatively 25 stationary clutch shifting lever 36, thus forcing this lever backwardly far enough to disengage the clutch. This movement swings the upper end of the lever 36 toward the 30 left, Figs. 1, 2 and 3, far enough to permit the latch 55 to drop in behind the lever, as shown in Fig. 3, and thus lock the clutch in its disengaged or inoperative position.

The machine now is in condition for the 35 doffing operation, and it has been brought into this condition entirely automatically, no attention on the part of the operator having been required up to this point. After doffing the operator winds down the builder 40 motion in the usual manner, and then throws the usual hand lever (not shown) which is connected with the rod 16 and moves this rod toward the left, Figs. 1 and 3, far enough to shift the belt 17 back on to the 45 fast pulley 18. At substantially the same time the operator releases the latch 50, thus starting the machine into operation again. As the rod 16 is moved toward the left, the bracket 20 engages the end of the rod 21 and 50 moves it toward the left, thus restoring the parts to the positions in which they are shown in Fig. 1, with the latch 24 engaging the stop 25, and the collar 41 bearing against the upper end of the lever 36.

55 It will now be appreciated that this invention provides a mechanism for automatically winding down the ring rail in such a manner that the amount of thread or yarn that will be wound on the bases of the bobbins can be controlled very accurately. In prior mechanisms of this type with which I am familiar, there has been no control over the stopping of the machine except that exercised by the full bobbin stop motion. 60 In the machine shown the full bobbin stop

motion simply initiates the operation of the stopping and wind down mechanisms, but the actual stopping of the machine is under the control of a device movable in conjunction with the ring rail so that the stopping 70 of the machine is not permitted until the ring rail has been wound down to a predetermined point. The amount of yarn which is wound on the bases of the bobbins therefore can be controlled in this mechanism 75 with an accuracy which has not been obtainable heretofore.

While I have herein shown and described the best embodiment of my invention that I have so far devised, it will be evident that 80 the invention could be embodied in other forms without departing from the spirit or scope thereof.

Having thus described my invention, what I desire to claim as new is:

1. In a ring spinning machine, the combination of mechanism for stopping the machine, automatic means for initiating the operation of said mechanism when the ring rail has risen to a predetermined point, and additional means for controlling the completion 90 of the operation of said mechanism.

2. In a spinning machine having a ring rail and a builder motion, the combination 95 of mechanism for stopping the machine, means independent of the builder motion for winding down the ring rail, and mechanism connected with the ring rail and responsive to changes in the elevation of said rail for controlling the operation of both said mechanism and said means.

3. In a ring spinning machine, the combination of mechanism for stopping the machine, automatic means for initiating the operation of said mechanism when the ring rail 105 has risen to a predetermined point, means for winding down the ring rail, and additional means movable in conjunction with the ring rail for restraining the action of said mechanism until the ring rail has reached substantially a predetermined point 110 in its downward movement.

4. In a ring spinning machine, the combination of mechanism for stopping the machine, means for winding down the ring rail, 115 a part movable in conjunction with the ring rail for initiating the operation of both said means and said mechanism when the ring rail has reached a predetermined point in its traverse, and another part movable in conjunction with said rail for restraining the action of said mechanism until the ring rail has reached a predetermined point in 120 its downward movement.

5. In a ring spinning machine, the combination of mechanism for stopping the machine, means for winding down the ring rail, mechanism connected with the ring rail and responsive to changes in the elevation of said rail for controlling the operation of both 125 130

said mechanism and said means, and a latch for holding said ring rail in its lowermost position.

6. In a ring spinning machine, the combination of a belt shifter, a spring, connections between said spring and said belt shifter for enabling said spring to shift the belt from one of its operative positions to another, a latch arranged to act on said connections to hold them against movement by said spring, means movable in conjunction with the ring rail of the machine for tripping said latch when the ring rail has reached a predetermined point in its upward movement, and an additional part movable in conjunction with said rail and operable through said connections after they have been released by said latch to restrain the movement of said shifter until the ring rail has dropped to substantially a predetermined point.

7. In a ring spinning machine having a ring rail and a builder motion, the combination of a belt shifter, a spring, connections between said spring and said belt shifter for enabling said spring to shift the belt from one of its operative positions to another, a latch arranged to act on said connections to hold them against movement by said spring, a rod arranged to be moved by the builder motion to release said latch when the ring rail has reached a predetermined point in its rise, driven mechanism for depressing said ring rail including a clutch under the control of said connections, an arm connected with said builder motion and arranged to be moved thereby, and a stop carried by said connections and arranged to be engaged by said arm immediately after the tripping of said latch whereby said arm is operative to interrupt the movement of said connections while the ring rail drops to a predetermined level.

8. In a ring spinning machine having a ring rail and a builder motion, the combination of a belt shifter, a rod connected with said shifter, a spring connected with said rod to move said shifter from its running to its idle position, a stop carried by said rod, a latch arranged to hold said

rod against movement under the influence of said spring, a part connected with said builder motion and arranged to be moved thereby to trip said latch at a predetermined point in the rise of the ring rail, mechanism including a clutch for depressing said ring rail, a spring for operating said clutch, connections between said clutch and said rod whereby the clutch is thrown in when said latch is tripped, and an arm arranged to be moved by said builder motion and operative to catch said stop and restrain the movement of said rod immediately after said said clutch has been thrown in and before the shifter has been moved substantially, said arm being arranged to release said stop when the ring rail has dropped to a predetermined level and thereby permit said spring to complete the movement of said shifter.

9. In a ring spinning machine having a ring rail and a builder motion, the combination of a belt shifter, a rod connected with said shifter, a spring connected with said rod to move said shifter from its running to its idle position, a stop carried by said rod, a latch arranged to hold said rod against movement under the influence of said spring, a part connected with said builder motion and arranged to be moved thereby to trip said latch at a predetermined point in rise of the ring rail, mechanism including a clutch for depressing said ring rail, a spring for operating said clutch, connections between said clutch and said rod whereby the clutch is thrown in when said latch is tripped, an arm arranged to be moved by said builder motion but operative to catch said stop immediately after said clutch has been released and to interrupt the movement of said rod until the ring rail has dropped to a predetermined level, means for disengaging said clutch automatically when the motion of the ring rail has been substantially completed, a latch for holding said ring rail in its lowermost position, and another latch operative when said clutch has been disengaged to hold it in its idle position.

JOSEPH H. LALIBERTE.
